UNITED STATES PATENT OFFICE

2,508,699

HAND HOIST SACK FILLER

Edward Welsh, Hatley, Wis.

Application February 27, 1946, Serial No. 650,561

5 Claims. (Cl. 226—58)

1

This invention relates to a sack filling device and it consists in the constructions, arrangements and combinations herein described and claimed.

It is a particular object of the invention to provide a mobile scoop device which may be manually moved into material to be sacked, elevated and discharged into a sack or other receptacle.

It is a still further object of the invention to provide a sack filling device of very simple construction embodying skid runners whereby the device may be readily moved and in which a sack to be filled may be supported in a manner to readily receive the material from an elevated scoop, all of which may be readily operated by a single workman.

Additional objects, advantages and features of invention will be apparent from the following description considered in conjunction with the accompanying drawing, wherein,

Figure 1 is a perspective view of the device illustrating its initial operative loading position.

Figure 2 is a side elevation of the device in position for discharge of the contents of the scoop device into a sack,

Figure 3 is an enlarged fragmentary top plan view illustrating the pivotal mounting of the scoop device.

Figure 4 is a cross section illustrating the mounting of a support for a sack to be filled.

Figure 5 is a fragmentary bottom view of the conveyor tube.

Referring to the drawing, there is illustrated a skid frame 10 consisting of a pair of elongated runners 11 connected in spaced parallel relation by means of suitable transverse braces 12.

Upon each of the runners 11 there is an upright 13 positioned rearwardly of the rearmost brace 12, each upright terminating in a bearing 14 for support of a shaft 15 for a purpose presently to be described.

Between the uprights 13 and a forward end of the runners 11, a brace rod 16 is secured by bolts, welding or otherwise, to afford rigidity to the structure.

The shaft 15 is held stationary in the bearings 14 and at a medial point of the shaft there is mounted an elongated tube 17 of suitable diameter, by means of a cradle presently to be described. The tube 17 is rockably supported upon the shaft, in the present instance, a collar 18 is illustrated secured to the outer periphery of the tube, and at the lower periphery of the collar 18, trunnions 19 are provided through which the shaft is extended.

2

The cradle for support of the tube is defined by a pair of operating arms 20 which are also rockably mounted upon the shaft 15, disposed upon respective side of the tube 17, these arms extending forwardly to a point substantially the length of the front portion of the runners 11 where they are connected by a transverse plate 21. The forward or scoop end 17' of the tube 17 rests upon the plate 21 and is secured thereto by means of a clamp collar 22. The arms 20 extend rearwardly beyond the uprights 13 a substantial distance and terminate in hand grips 23. A handle bar 24 is connected to the arms 20 a distance inwardly of the hand grips and are suitably braced as at 25. The handle bar extends upwardly a suitable height so as to provide ample leverage to effect tilting movement of the cradle and associated parts with a minimum of effort.

A scoop 26, which may be of any suitable construction with respect to its forward edge, depending upon the material being handled, is detachably mounted at the scoop end 17' of the tube. In the present instance, this is accomplished by providing the rear end of the scoop 26 with a contour corresponding to the circumference of the tube. With this part of the scoop disposed upon the tube and resting upon the plate 21, the clamp collar 22 will hold the scoop in proper rigid position in advance of the tube so as to feed material thereto.

An annular ring 27 is rigidly fixed to the shaft 15 by means of bolts or rivets 28, the ring extending in a horizontal plane and centralized with respect to the discharge end 29 of the tube. In order to suspend a bag 30 or similar container from the ring in an open receiving position, suspension hooks 31 are formed upon the periphery of the ring.

In use, it being assumed that the parts will be in the position shown in Figure 1, the scoop 26 resting upon the floor where material to be sacked is deposited. The device is advanced toward the material by exerting a pushing movement on the handles 23, the runners 11 moving easily and smoothly upon the floor, until the scoop 26 engages the material. Further advancing movement of the device will cause material to move into the scoop and thence into the tube by way of the open end 17'. The device may be retracted and advanced into the material until a desired amount of material has been forced into the tube. Now, in order that the material may be transferred to the sack 30, it is only necessary to grab the handle bar 24 and exert a downward pull, thus elevating the

tube to the position shown in Figure 2, when the material will move along the tube and discharge into the sack. The operation is repeated until the sack is filled, which may then be removed and an empty sack is then placed upon the ring 27 and similarly filled.

On occasion it may be desirable to screen the material before being sacked, and in Figure 5, I have shown the tube with a portion of the bottom wall as a screen element 32. It will be apparent that as the material passes over the screen member, undesired particles will pass outwardly of the tube. When the screen is not required, the opening 33 in the tube may be closed by a suitable plate by bolts engaged in the threaded openings 34.

From the foregoing description it will be seen that I have provided a device which may be operated to quickly fill sacks by a single workman and this is accomplished without the need for back bending exertions as required by present day practices.

While I have shown and described a preferred form of the device, this is by way of illustration only and I consider as my own, all such modifications in construction as fairly fall within the scope of the appended claims.

I claim:

1. In a hand hoist sack filling device, a pair of parallel runner members, an upright on each runner member, a transverse shaft fixed in the upper ends of each upright, a cradle rockably mounted on said shaft, an elongated tube disposed medially of said shaft and having one end rockably mounted thereon, said cradle including a plate for rigid securing of the other end of said tube, a scoop carried by said other end of the tube, handle means associated with said cradle to move the device so as to present the scoop into material disposed upon a floor or the like, a sack detachably connected in advance of the rockably connected end of the tube and a handle bar connected with said cradle for tilting said tube.

2. In a hand hoist sack filling device, a pair of runner members, brace members connecting

said runner members in parallel relation, an upright on each runner positioned rearwardly of the rearmost brace member, each upright having a bearing adjacent the upper end thereof, a shaft fixed in said bearings and extending transversely of the runners, a cradle, said cradle consisting of a pair of elongated arms, each arm being pivotally mounted on said shaft and spaced slightly inward of respective uprights, 5 one end of said arms terminating in respective handles, the other end of said arms being connected by a transverse plate, an elongated tube of a length extending from said shaft and beyond said transverse plate, the end of the tube 10 adjacent the shaft being rockably connected thereto and the end adjacent the transverse plate being fixed thereto, said tube being disposed medially of said cradle, a scoop connected to the last named end of the tube and normally occupying a position to engage a supporting surface, a receptacle support on said shaft in advance of the rockable end of the tube, and an upright handle bar connected to said arms in advance of said handles.

3. The structure of claim 2 in which said scoop is detachably mounted to said tube.

4. The structure of claim 2 in which each of said uprights is braced by a diagonal rod extended between respective runners and uprights.

5. The structure of claim 2 in which the handle bar consists of braced upright portions connected to respective arms of the cradle and a transverse hand bar portion.

EDWARD WELSH.
